UNITED STATES PATENT OFFICE.

FREDERICK HIRAM LULL, OF PATCHOGUE, NEW YORK, AND EDWARD CHARLES WANNER, OF SAN FRANCISCO, CALIFORNIA.

CONDENSER.

1,248,536.

Specification of Letters Patent.

Patented Oct. 16, 1917.

Application filed January 4, 1917. Serial No. 140,529.

To all whom it may concern:

Be it known that we, FREDERICK H. LULL and EDWARD C. WANNER, citizens of the United States, and residents of Patchogue, 5 in the county of Suffolk, State of New York, and of San Francisco, in the county of San Francisco, State of California, respectively, have invented certain new and useful Improvements in Condensers, of which the following is a specification.

Our invention relates to distillation, as of water or other liquids, mashes and the like, and one of the main objects thereof is to provide a condenser adapted to be superposed 15 upon an ordinary kitchen utensil, such as a teakettle, coffee pot, or other container for the matter to be distilled, and a further object is to provide for rapid distillation by the provision of a water-jacket and means for 20 insuring a circulation of cooling water therethrough.

Our invention is fully described in the following specification, of which the accompanying drawing forms a part, said drawing illustrating one embodiment of the condenser, shown in section, arranged upon an ordinary tea-kettle, also partly in section.

Referring to the drawing, 1 represents a tea-kettle having the usual opening 2 in the 30 top thereof adapted to be closed by a cover, not shown, and a spout 3, our condenser 4 being arranged in the opening 2 in a steam-tight manner, and, when our condenser is used with a tea-kettle or the like, a cork 5 is fitted into the spout 3 in a steam-tight 35 manner, and the liquid or other matter to be distilled is placed in the container 1 previous to the insertion of the lower tapered tubular portion 6 of the condenser into the 40 opening 2.

Arranged above the portion 6 and preferably integral therewith is a casing 7 joined to the portion 6 in such manner as to provide a gutter 8 having an outlet pipe 9, 45 these parts being preferably formed of copper although not necessarily, and the casing 7 is inclosed within a jacket 10 having a port 11 in the top thereof communicating with a pipe 12, and having an opening 13

in the bottom thereof communicating with 50 a stand-pipe 14 adapted to receive a funnel 15 under certain conditions, of such length as to have its receiving end on a higher level than that of the port 11 and connected pipe 12. 55

The material to be distilled is placed within the container 1, the condenser arranged thereon, the cork 5 placed in position, and the container placed over a source of heat, the material being vaporized 60 and deposited upon the inner surface of the casing 7 in the form of condensation and passing to the gutter 8 and outlet 9, the condensation being expedited by cool water within the water-jacket 10, and a rapid distillation results. 65

Where no water under pressure is available the funnel may be utilized to admit water to the water-jacket, a circulation being assured because of the higher level 70 of the said funnel but, when water under pressure is available, a tube leading from the water supply may be connected with either the pipe 12 or the stand-pipe 14, the funnel being then dispensed with. 75

The condenser is very simple though entirely practical and, because of the lack of necessity for providing a special container 1, is comparatively inexpensive, and is of relatively great capacity because of the 80 simple though highly efficient water circulating system for expediting the condensation of the vapors.

Our condenser is especially adapted for household use and may be made of different 85 sizes and of different materials, and it may also be made to fit certain types of kitchen utensils, but we do not confine ourselves to size, material, or shape provided, however, that the condenser proper is adapted to be 90 used with a suitable container not initially a part thereof.

Having fully described our invention, what we claim as new, and desire to secure by Letters Patent, is:—

A condenser attachment for tea kettle or the like, comprising a tubular member forming the bottom part of the condenser, a cas-

ing over the tubular member and connected with the top edge of the latter by a compound fold whereby an annular gutter is formed in the bottom of the casing and around the member, a jacket surrounding the casing, and separate tubes for the inlet

and outlet of water going through the jacket, the outlet of the casing passing through one of the tubes.

FREDERICK HIRAM LULL.
ED. CHARLES WANNER.
